UNITED STATES PATENT OFFICE.

OTTO S. PIKE, OF MALDEN, MASSACHUSETTS, ASSIGNOR TO AMERICAN PNEUMATIC SERVICE COMPANY, OF DOVER, DELAWARE, A CORPORATION OF DELAWARE.

PNEUMATIC-DESPATCH-TUBE APPARATUS.

SPECIFICATION forming part of Letters Patent No. 790,457, dated May 23, 1905.

Application filed February 12, 1904. Serial No. 193,234.

To all whom it may concern:

Be it known that I, OTTO S. PIKE, of Malden, in the county of Middlesex and State of Massachusetts, have invented certain new and useful Improvements in Pneumatic-Despatch-Tube Apparatus, of which the following is a specification.

My invention relates to receiving-terminals for pneumatic-despatch apparatus; and its object is to provide a means for receiving a carrier from the pneumatic transmission-tube without allowing air from the transmission-tube to escape into the atmosphere violently.

Another object of my invention is to provide means whereby the carriers may be brought entirely into the receiving-chamber promptly and automatically and promptly discharged therefrom.

The terminal consists, essentially, of a receiving-chamber forming a continuation of the transmission-tube, a valve between the receiving-chamber and the transmission-tube, a valve between the receiving-chamber and the atmosphere, and mechanism for operating the valves.

Mounted on the receiving-chamber is a relief-valve consisting, essentially, of a body having a passage-way through it connecting the receiving-chamber with the atmosphere, a piston normally closing the opening between the receiving-chamber and the atmosphere, a spring which tends to move the piston so as to open the passage between the receiving-chamber and the atmosphere, a trigger normally locking the piston in its normal position, a spring tending to hold the trigger in a locking position, a piston attached to the trigger for unlocking the same, and mechanism for returning the relief-valve to its normal position.

My invention consists of certain novel features hereinafter described, and particularly pointed out in the claims.

In the accompanying drawings, which illustrate a construction embodying my invention, Figure 1 shows an elevation of the terminal with valves and mechanism in their normal positions. Fig. 2 is a plan view of the same.

Fig. 3 is an elevation, partly in section, showing valves and mechanism in position for discharging a carrier from the terminal. Fig. 4 is a section through the receiving-chamber and valves when the valves are in their normal position. Fig. 5 is a similar section showing the valves in position for discharging a carrier. Fig. 6 is a section through the piston slide-valve and auxiliary cylinder hereinafter described, showing parts in their normal positions. Fig. 7 shows a side elevation of the relief-valve with parts in normal position. Fig. 8 is a longitudinal section of the same, with some of the parts in the position assumed during the discharge of a carrier. Fig. 9 is a plan view of the same with parts in normal position. Fig. 10 is a section on the line $\alpha\alpha$, Fig. 8. Fig. 11 is a similar view to Fig. 8, but with parts in the position assumed during the advance of the carrier into the receiving-chamber. Figs. 12, 13, and 14 are respectively plan view, side and end elevations of part of the relief-valve. Fig. 15 is a horizontal section through the piston slide-valve, showing the same in the opposite position to that shown in Fig. 6.

Like letters of reference refer to like parts throughout the several views.

A is the end of the transmission-tube, the arrow-head B showing the direction in which the carrier travels.

A^3 is a grated T, having the ports A^5 leading from its interior into the annular space A^6 surrounding. The air coming through the tube A passes through the ports A^5 into the annular space A^6 and thence into the pipe A^4 .

A' is a receiving-chamber forming a continuation of the transmission-tube and normally closed to the atmosphere by the valve A^7 .

A^2 is a valve interposed between the receiving-chamber A' and the T A^3 and normally open. The valves A^2 and A^7 are so constructed that when their axes are placed in line with the axis of the receiving-chamber A' carriers can pass through them freely. The valves A^2 and A^7 are suitably mounted on trunnions, the front trunnions being attached to the cranks A^8 A^9 , respectively. The crank A^8 is

connected to the bell-crank A^{10} by the connecting-rod B' . The crank A^9 is connected to the bell-crank B^2 by the connecting-rod B^3 . The bell-cranks A^{10} and B^2 are operated by 5 rollers B^4 and E , respectively mounted on the wrist-plate B^5 and working between the jaws B^6 and B^7 of the bell-cranks A^{10} and B^2 , respectively. The wrist-plate B^5 is in turn actuated by the piston B^8 in the cylinder B^9 , 10 the piston B^8 being connected to the wrist-plate B^5 by the piston-rod B^{10} and the connecting-rod C . The piston B^8 is operated by a supply of compressed air or other fluid admitted to the cylinder B^9 through the pipes 15 C' and C^2 . The supply of compressed air above referred to is controlled by the piston slide-valve C^3 in the valve-chest C^4 , Fig. 6. This valve-chest C^4 is fitted with ports C^5 C^6 , leading to the pipes C^2 and C' , respectively. 20 The construction of the slide-valve C^3 and valve-chest C^4 is well known in the art.

The supply of compressed air for operating the mechanism is introduced into the valve-chest C^4 through the pipe C^7 from any suitable source. Attached to the valve-chest C^4 25 is an auxiliary cylinder C^8 , Fig. 6. In this cylinder C^8 is an auxiliary piston C^9 , and attached to the piston C^9 is the piston-rod C^{10} . The valve C^3 is pushed to the right by the 30 piston C^9 , as hereinafter described. The valve C^3 is pushed to the left by the rod D , Figs. 1, 2, and 3, which is attached to the finger D' , this finger being operated by the carrier D^2 as the latter is discharged from the terminal. 35

From the right-hand end of the auxiliary cylinder C^8 the pipe D^3 is led into the annular space A^6 of the $T A^3$. The pipe D^4 leads from the receiving-chamber A' at a point near the valve A^7 to the left-hand side of the piston C^9 40 in the cylinder C^8 .

The piston J , Fig. 8, is normally held to the right by the spring J' . The pipe J^2 leads from the left of the piston J to the annular space A^6 in the $T A^3$, and the pipe J^3 leads 45 from the right of the piston J to a point in the receiving-chamber A' near the valve A^7 , so that normally the piston J is balanced, as far as the air-pressure is concerned. After the carrier has passed through the $T A^3$ the 50 excess pressure produced by the energy of the carrier is transmitted through the pipe J^3 , and thus forces the piston J to the left, and with it the trigger J^4 , as shown in Fig. 11. As the trigger J^4 moves to the left it releases 55 the block J^5 , which is attached to the spindle J^6 of the piston-valve J^7 . The spring J^8 then forces the piston-valve J^7 upward, opening the passage J^9 in the relief-valve, connecting the body K^3 , the receiving-chamber A' by the 60 port L , and the atmosphere through port L' , as shown in Fig. 11. This relieves the excess pressure in the receiving-chamber A' , and thus allows the carrier to be forced entirely into the chamber A' by the pressure of the air in the 65 transmission-tube A .

As the carrier advances into the valve A^2 and receiving-chamber A' the pressure generated in front of the carrier forces the piston C^9 in the cylinder C^8 to the right, carrying with it the piston-valve C^3 . This allows 70 compressed air from the pipe C^7 to pass through the port C^6 into the pipe C' , thence to the left of the piston B^8 in the cylinder B^9 . This supply of compressed air forces the piston B^8 to the right, at the same time moving 75 the wrist-plate B^5 a portion of a revolution. During the first portion of this movement the bell-crank A^{10} is revolved by means of the roller B^4 working in the jaws B^6 of the bell-crank A^{10} , thus revolving the valve A^2 into 80 the position shown in Figs. 3 and 5. As the valve A^2 reaches this position the roller B^4 disengages from the jaws B^6 of the bell-crank A^{10} , and the locking-arc D^9 , mounted on the wrist-plate B^5 , engages with the curved portion 85 D^{10} of the bell-crank A^{10} and locks the bell-crank A^{10} in position. During the motion of the bell-crank A^{10} the bell-crank B^2 is similarly locked by the locking-arc D^9 . As the roller B^4 disengages from the jaws B^6 the 90 roller E engages the jaws B^7 of the bell-crank B^2 , and during the latter part of the movement of the wrist-plate B^5 the valve A^7 is opened into the position shown in Figs. 3 and 95 5. Leading from the $T A^3$ to a point in the receiving-chamber A' on the right and close to the valve A^2 is a pipe E' . In this pipe E' is a check-valve E^2 , which allows the air to pass in the direction of the arrow E^3 , but not in the opposite direction. As the valve A^7 opens, 100 as above described, the pressure in the receiving-chamber A' escapes into the atmosphere. The pressure in the transmission-tube A causes the air to flow through the pipe E' behind the carrier in the receiving-chamber 105 A' , and this forces the carrier out, through the valve A^7 , into the receiving-trough E^4 . As the carrier slides along the trough E^4 it strikes the finger D' and forces the piston-valve C^3 to the left, as above described. This 110 allows compressed air from the pipe C^7 to pass into the port C^5 and thence through the pipe C^2 to the right of the piston B^8 , thus forcing the piston B^8 to the left into its normal position, the valve A^7 closing and the 115 valve A^2 opening successively in a manner similar to their opposite motions, as described above, and thus restoring the valves to their normal positions, Fig. 4. When the piston B^8 moves to the right, as previously described, 120 the air on the right of the piston is exhausted into the atmosphere through the pipe C^2 , port C^6 , and through the opening E^5 in the valve-chest C^4 . Similarly, when the piston B^8 moves to the left the air to the left of the piston is 125 exhausted into the atmosphere through the pipe C^7 , the port C^6 , and the opening E^5 in the valve-chest C^4 . As a carrier passes by the finger D' or when a carrier is removed from the trough E^4 said finger D' is forced back to 130

its normal position, as shown in Fig. 1, by the spring E⁶ on the rod D.

The air from the pipe C⁷ is prevented from escaping directly into the atmosphere by the 5 piston slide-valve C³, which compels the air from said pipe C⁷ to pass into the pipe C' or pipe C², according as the piston slide-valve C³ is in the right-hand or left-hand position. (See Figs. 6 and 15.) The air from the pipe 10 C⁷ passes through the pipe C' or C² to the cylinder B⁹, as before described.

On the rear trunnions of the valve A⁷ is a pin K⁴, Fig. 2. One end of the connecting-rod J¹⁰ rides on the pin K⁴. When the valve 15 A⁷ opens, as described, it draws the connecting-rod J¹⁰ downward, thus revolving the shaft K by means of the crank K⁵, thereby pulling the fork K', which is pinned to the shaft K, downward. The fork K' bears on 20 the shoulders K² of the block J⁵, and thus forces the piston-valve J⁷ downward, compressing the spring J⁸ and closing the passage J⁹ between the receiving-chamber A' and the atmosphere. The proportions of the mechanism 25 are such that the top of the block J⁵ is pushed down slightly below the bottom of the trigger J⁴ by the fork K', as shown in Fig. 8. When the top of the block J⁵ passes the bottom of the trigger J⁴, the trigger J⁴ is 30 forced to the right by the spring J', also by the air-pressure in the transmission-tube A, which is transmitted to the left of the piston J through the pipe J². It will be noticed that when the valve A⁷ opens, the air-pressure 35 sure on the right of the piston J escapes into the atmosphere through the pipe J³, so that the entire pressure of the air in the transmission-tube is effective in forcing the piston J to the right. As the spring J' always tends 40 to force the piston J to the right and is also made adjustable by means of the screw K⁶, it may be used as a means for preventing the compressed air generated by the advancing carrier from unlocking the block J⁵ until the 45 pressure generated by the carrier has nearly or quite reached its maximum. When the valve A⁷ returns to its normal position, the fork K' is returned to its normal position, as shown in Fig. 7.

Having thus described the nature of my invention and set forth a construction embodying the same, what I claim as new, and desire to secure by Letters Patent of the United States, is—

1. In a pneumatic-despatch-tube apparatus, a transmission-tube, a terminal, a receiving-chamber in said terminal for receiving and cushioning the carriers, an air-opening in said receiving-chamber for the escape of air compressed ahead of the carrier, a valve controlling said opening for regulating the escape of the air compressed ahead of the carrier, locking means for holding said valve closed, mechanism operated by the air compressed ahead 60 of the carrier for releasing said locking means,

and means for opening said valve to allow the escape of compressed air after the release of said locking means.

2. In a pneumatic-despatch-tube apparatus, a transmission-tube, a terminal, a receiving-chamber in said terminal for receiving and cushioning the carriers, an air-opening in said receiving-chamber for the escape of air compressed ahead of the carrier, a valve controlling said opening for regulating the escape of the air compressed ahead of the carrier, locking means for holding said valve closed, mechanism operated by the air compressed ahead of the carrier for releasing said locking means, means for opening said valve to allow the escape of compressed air after the release of said locking means, and mechanism operated by the carrier upon its discharge from said receiving-chamber for closing said valve. 75

3. In a pneumatic-despatch apparatus, a transmission-tube, a receiving-chamber in said terminal for receiving and cushioning the carriers, an air-opening in said receiving-chamber for the escape of air compressed ahead of the carrier, a valve controlling said opening for regulating the escape of the air compressed ahead of the carrier, locking means for holding said valve closed, mechanism operated by the air compressed ahead of the carrier for releasing said locking means, means for opening said valve to allow the escape of compressed air after the release of said locking means, mechanism operated by the carrier upon its discharge from said receiving-chamber for closing said valve, and means for holding said valve closed, mechanism operated by the air compressed ahead of the carrier for releasing said locking means, means for opening said valve to allow the escape of compressed air after the release of said locking means, mechanism operated by the carrier upon its discharge from said receiving-chamber for closing said valve, and means for moving said locking means into position to hold said valve against opening. 90

4. In a pneumatic-despatch-tube apparatus, a transmission-tube, a terminal, a receiving-chamber in said terminal for receiving and cushioning the carriers, an air-opening in said receiving-chamber for the escape of air compressed ahead of the carrier, a valve controlling said opening for regulating the escape of the air compressed ahead of the carrier, locking means for holding said valve closed, mechanism operated by the air compressed ahead of the carrier for releasing said locking means, means for opening said valve to allow the escape of compressed air after the release of said locking means, mechanism operated by the carrier upon its discharge from said receiving-chamber for closing said valve, and yielding means for moving said locking means into position to hold said valve against opening. 105

5. In a pneumatic-despatch-tube apparatus, a transmission-tube, a terminal, a receiving-chamber in said terminal, a valve between the transmission-tube and the receiving-chamber 125 and normally open, a valve between the receiving-chamber and the atmosphere and normally closed, mechanism common to said valves for operating the same, a cylinder, a piston in said cylinder connected to said mech- 130

anism, an air-supply for operating said piston to move said valves, an air-opening in said receiving-chamber for the escape of air compressed ahead of the carrier, a valve controlling said opening for regulating the escape of air compressed ahead of the carrier, locking means for holding said air-opening-controlling valve in its closed position, mechanism operated by the air compressed ahead of the carrier for releasing said locking means, means for opening said air-opening-controlling valve to allow the escape of air compressed ahead of the carrier after the release of said locking means, and mechanism operated by the carrier upon its discharge from said receiving-chamber for opening the valve between the transmission-tube and the receiving-chamber and closing the valve between the receiving-chamber and the atmosphere and for closing the air-opening-controlling valve.

6. In a pneumatic-despatch-tube apparatus, a transmission-tube, a terminal, a receiving-

chamber in said terminal for receiving and cushioning the carriers, an air-opening in said receiving-chamber for the escape of air compressed ahead of the carrier, a valve controlling said opening for regulating the escape of the air compressed ahead of the carrier, locking means for holding said valve closed, mechanism operated by the air compressed ahead of the carrier for releasing said locking means, means for opening said valve to allow the escape of compressed air after the release of said locking means, and mechanism for closing said valve upon the discharge of the carrier from said receiving-chamber.

In testimony whereof I have signed my name to this specification, in the presence of two subscribing witnesses, this 4th day of February, A. D. 1904.

OTTO S. PIKE.
